DEVICE FOR MEASURING ENERGY INPUT TO RAISING ROLLERS OF TEXTILE RAISING MACHINES

John M. Magarshack, Heaton Moor, Stockport, and Edward Moss, Didsbury, Manchester, England, assignors to The British Cotton Industry Research Association, Didsbury, England, a British association of Shirley Institute

Filed Apr. 28, 1959, Ser. No. 809,553
4 Claims. (Cl. 26—33)

This invention concerns nap raising machines as used in the textile industry. It is concerned particularly with rotary nap raising machines and especially (though not exclusively) rotary nap raising machines of the double action type.

Rotary nap raising machines generally consist basically of a large cylinder fitted with end plates or rings, a number, usually from eighteen to thirty six, of raising rollers journaled between the end plates so as to lie parallel to and above the surface of the cylinder, the rollers being fitted with card clothing, means for passing the fabric to be raised over the raising rollers, means for driving the cylinder, and variable speed means for driving the raising rollers. In double action machines the teeth of the card clothing point in one direction on one series of alternate raising rollers, and in the opposite direction on the other series of alternate rollers, and there are independent variable speed drive means for each series. In operation the cylinder normally rotates in the same direction as the cloth travels (but can rotate in the opposite direction) and carries the raising rollers with it. The raising rollers also rotate on their axes, the direction of movement of their peripheries relative to the direction of travel of the cloth depending on whether they are raising or felting. The card clothing on the raising rollers effects the raising, the rollers having the teeth of their card clothing pointing in the direction of the cloth movement being known as the pile rollers, and the rollers with the teeth of the card clothing pointing in the opposite direction being known as the counter pile rollers.

Two main factors control the amount of raise per run on a particular raising machine, and these are firstly, the cloth speed and, secondly, the raising action. The raising action depends on the relative speeds of the cloth and the card clothing on the raising rollers. A change in cloth speed will therefore, alter the action for given roller speeds. Since in most machines the gear boxes used to alter the roller speeds are not linear and the drives to the raising rollers are not fully positive, it is not possible accurately to relate the raising action settings (i.e. the speeds of the raising rollers) to raising action at different cloth speeds, or even at the same cloth speed when there is slip in the gear boxes and drives. It is possible, of course, for example, by means of differential drives, to arrange for automatic alteration of the action settings to compensate for a change in cloth speed, and also to provide a fully positive drive to the raising rollers. Even when such measures are taken, there is no direct indication of the raising action, for example in the double action machine of the pile and of the counter-pile rollers, or of whether these actions are balanced as they should be for balanced raising. Similar considerations apply to single action machines although there is here no question of the balancing of two opposite actions.

The factors just referred to make it necessary for the operator of a rotary nap raising machine of known type, especially such a machine having both pile and counter-pile rollers, to have considerable experience and skill before he can practice satisfactory results.

The objects of the present invention is to provide

means whereby an indication of the amount of raising action being applied by any particular raising roller or rollers irrespective of the particular details of the machine construction, can be obtained.

5 The invention is based upon the appreciation of the fact that the raising action of one or more rollers depends directly on the energy input to the roller or rollers. According to the present invention therefore, a nap raising machine has means for indicating the energy input to one or more sets of rollers. In practicing the invention the operator will know what raising effect will be obtained at a given energy input and he will adjust his drive means accordingly. He will also, where more than one set of raising rollers are used, be able to control the relationship between their respective raising actions.

10 The invention will now be described further, by way of example, with reference to the accompanying drawings, in which:

15 FIG. 1 is a diagrammatic end view of a raising machine;

20 FIG. 2 is an elevation, partly in section of one end of a roller and its associated parts on a raising machine, means being provided whereby an indication of the energy input to the roller may be had according to the invention;

25 FIG. 3 is a sectional end elevation on the line 3—3 of FIG. 2;

30 FIGS. 4^a, 4^b, 4^c, and 4^d are diagrams illustrating one electrical circuit; and

35 FIGS. 5^a, 5^b, 5^c, and 5^d are similar diagrams illustrating an alternative electrical circuit.

40 Referring to FIG. 1 there is illustrated diagrammatically in end view a raising machine of conventional type showing the main elements which comprises a cylinder 10, and raising rollers 11 journaled in end rings thereof. Cloth C passes over the raising rollers 11 in contact therewith. Details of the drive are omitted in the figure which is intended only to illustrate the general arrangement of the working parts and the cloth movement in relation thereto. As previously mentioned the cylinder may be rotated in either direction.

45 In the machine being described there are both a series of pile and a series of counter-pile rollers and one roller of each series is provided with dynamometer means for indicating the energy input. The subsequent description will be of one side of the machine and will relate to a roller of one series for which such means is provided. It will be understood that a similar arrangement will be provided at the other side of the machine in respect to the roller of the other series for which such means is provided.

50 Referring to FIGS. 2 and 3 the end of the roller 11 carries, adjacent one of the cylinder rings 12 in which it is journaled, a loose pulley 13 and two switch means in the form of commutators 14, 15. The commutators 14, 15 are disposed between the loose pulley 13 and the cylinder ring 12, the one commutator 15 nearer the cylinder ring 12 being keyed to the roller 11 for rotation therewith and the other commutator 14 being secured by screws 16 (one only of which is seen in the figures) to the loose pulley 13 for rotation with that pulley. Suitable anti-friction bearings are provided for the parts which rotate with respect to the roller 11. The loose pulley has V-grooves and clamp plates 17, on a belt wheel 20, are provided for gripping in well-known manner the V-belts 20^a, which transmit the drive in an adequately positive manner thereto and to the driving pulleys of the other rollers. The drive is further transmitted to the roller 11 from the pulley 13 through a leaf spring 18 of suitable stiffness held securely by clamp 19 on the roller 11 in a radial position relative to the latter.

Further, brackets 21, 22 extend from the side of the pulley 13 and a pair of grub screws 23, 24 are used to secure the outer end of the leaf spring 18 as illustrated more clearly in FIG. 3. Brackets 21a, 22a are secured to the pulley for balancing purposes.

A brush 25 is mounted so as to contact the periphery of the commutator 14 and another brush 26 is likewise mounted with respect to commutator 15. For mounting purposes spring steel clips 17, 28 are used, these being firmly secured to the cylinder ring 12 and insulated from the brushes. Leads 25a and 26a connect the brushes 25, 26 to slip-rings (not shown) on the ring 12 whereby the brushes may be connected in an electrical circuit as will later be described.

It will be clear that in operation, the deflection of the leaf spring 18 will be proportional to the torque being transmitted by the pulley 13 to the roller 11. Likewise there will be a rotational movement of the pulley 13 with respect to the roller 11, and thus between the two commutators, the magnitude of which, relative to a datum, will also be proportional to the torque transmitted from pulley to roller.

It has been found convenient to use commercially available commutators 14, 15, each having for example, forty-eight segments, and to connect every third segment together. The interconnected segments of one commutator, as described later, are connected to the interconnected segments of the other, and the connection may be through the roller 11, or through a flexible lead.

If now the commutators 14, 15 and their brushes 25, 26 are connected through the slip-rings to a source of electric power and a meter in a suitable manner, the meter will indicate the torque applied to the roller by the pulley.

The circuit will be designed so that the indication is given in the manner now described. If an electric potential is applied across the connected segments of each commutator and its brush, a current will pass which has a square wave characteristic. By suitably synchronising the commutators at a transmitted torque just sufficient to overcome the frictional losses of the whole system and by arranging the circuit in any one of a number of alternative ways, a resultant current having a square wave characteristic of minimum mark-to-space ratio is obtained. Transmission of increased torque to deal with the raising load will cause a relative angular deflection of the two commutators, and with a suitable leaf spring between pulley and shaft this will cause a change in the mark-to-space ratio, and therefore in the mean current, over the whole working range, such change being proportional to the raising torque. It is a straightforward matter to arrange for the torque value to be read off on a calibrated meter of suitably slow response.

In one suitable circuit (FIG. 4a) the two sets of connected segments A, B are connected in series. Between the two brushes are connected, also in series, a battery V, a limiting resistance R and the meter M.

The relative position of the brushes with respect to their commutators is adjusted so that when there is no angular displacement between the driving and driven members, B switches on as A switches off, as shown in the brush timing diagram (FIG. 4b). When there is some relative displacement B switches on before A switches off and a square-wave current pulse flows through the meter (FIGS. 4c and 4d). In the undeflected condition B switches off before A switches on again. This is necessary in order to avoid current flowing for negative deflections if there is some vibration in the drive that is not transmitted by the spring. This overlapping off region must be of an amount not less than the amplitude of the vibration. The number of segments per ring, which must be sufficiently large so that the switching frequency is much greater than the natural frequency of the meter, is restricted by the vibration present. Depending on the speed of the shaft and the

maximum torque applied to it therefore, the minimum spring strength can be determined for the maximum angular deflection, consistent with a reasonable number of segments. The conducting segments of one commutator are connected to those of the other and are either connected to earth through the machinery, or the commutators are joined by means of a lead which is sufficiently flexible for it to exert no restraining force on the spring. In the latter case no current need go through the mechanical parts:

In another circuit (FIG. 5a) the meter M is connected to one of the brushes, and that brush, its commutator and the meter are connected in parallel both with the other commutator and its brush, and also with a battery V and limiting resistance R, the commutator part of the circuit being earthed. In this circuit the two brushes can if desired, be replaced by a single brush in contact with both commutators. FIG. 5b is the no deflection timing diagram, while FIGS. 5c and 5d show a deflection timing diagram and the current pulses respectively.

Other circuits are possible and we do not limit ourselves to the two examples just described.

We have found that satisfactory results are obtained by taking a reading from only one of the pile rollers 25 and one of the counter-pile rollers, but dynamometers may be fitted to more than one roller of a series if desired.

By the arrangement just described it is possible to obtain a quantitative indication of the raising action whatever the cloth speed, and also to obtain balance between the actions of the pile and counter-pile rollers.

In operation the meter reading of the raising action will be set to a required value which will have been previously determined for each type of cloth, but will be obtainable without reference to roller or cloth speeds. The operator will be able to raise in or out of balance, or vary the action while raising, in a far more controlled manner than is at present possible. Also he will be able to change the cloth speed or the tension while maintaining the same raising action by keeping the same meter readings.

The operation of the dynamometer arrangement will be as indicated irrespective of the machine characteristics, that is to say, for example, whether the drives to the raising rollers are positive or not.

The invention is not limited to the details of the particular embodiment just described since any convenient dynamometer arrangement may be used instead of the one particularly described hereinbefore.

Although we have described in our preferred embodiment of the invention, the provision of a dynamometer at the end of the raising roller, it will be appreciated that the energy measurement can be taken anywhere in the drive. However, the more remote the dynamometer from the roller, the more desirable it is to calibrate the indicating instrument to allow for power losses in the later part of the drive.

We claim:

1. In a nap raising machine, a series of nap raising rollers, a dynamometer associated with one of said series of rollers at one end of the latter, said dynamometer comprising a drive transmission which includes a driving pulley and deflectable means interposed between said pulley and said roller, said deflectable means being subject to a deflection whose magnitude is in direct proportion to the energy being transmitted to the roller, and means for indicating the magnitude of said deflection.

2. In a nap raising machine, the elements defined in claim 1, in which said indicating means comprises a first switch having a rotary switch member mounted for movement with said pulley, a second switch having a rotary switch member mounted for movement with said roller, whereby the mutual angular displacement of said switch member from a given datum is proportional to

said deflection, an electric circuit responsive to the action of said switches, and a meter in said circuit.

3. In a nap raising machine, the elements defined in claim 1, in which said indicating means comprises a first switch having a rotary switch member mounted for movement with said pulley, a second switch having a rotary switch member mounted for movement with said roller, whereby the mutual angular displacement of said switch members from a given datum is proportional to said deflection, each switch member being a commutator and each switch including a fixed brush engaging said commutator, an electric circuit responsive to the action of said switches, and a meter in said circuit.

4. In a nap raising machine, the elements defined in claim 1, in which said indicating means comprises a first switch having a fixed brush and a commutator mounted for movement with said pulley, a second switch having a fixed brush and a commutator mounted for movement with said roller, whereby the mutual angular displacement of said commutators from a given datum is proportional to said deflection, an electric circuit re-

sponsive to said angular displacement of said commutators, and a meter in said circuit, each commutator having a number of segments electrically interconnected, the interconnected segments of one being electrically connected to the interconnected segments of the other, said brushes being so arranged that when there is no displacement from said datum the brushes contact their respective commutator segments in a sequential pattern which produces no meter reading.
